JOHN W. HOBBS, OF MOLINE, ILLINOIS, ASSIGNOR, BY MESNE ASSIGNMENTS, TO THE DUFF-NORTON MANUFACTURING COMPANY, OF PITTSBURGH, PENNSYLVANIA, A CORPORATION OF PENNSYLVANIA

LIFTING JACK

Application filed March 28, 1928. Serial No. 265,291.

My invention relates to lifting jacks whose rams or lifting members are pneumatically controlled.

My invention has for its object the provision of mechanism for relieving such a ram of its operating influence upon reaching a predetermined position with respect to its jack frame. In carrying out my invention, I employ an air operated ram operating motor, valve mechanism controlling the flow of compressed air through the motor, and mechanism governing the valve mechanism and governed by the ram of the corresponding jack in a manner to cut off the flow of air to the motor when the ram reaches each end of its travel.

The invention will be more fully explained in connection with the accompanying drawings in which Fig. 1 is a view, partially in sectional elevation and partially in full elevation, of the preferred embodiment of the invention; Fig. 2 is a sectional view on line 2—2 of Fig. 1; Fig. 3 is a sectional view on line 3—3 of Fig. 1; Fig. 4 is a view diagrammatically illustrating the invention, the portions appearing in full lines showing the condition which obtains when the ram is to be lifted from its lowermost position, the portions illustrated by the dot and dash lines showing the condition which obtains when the ram has reached its uppermost position, the air motor then being stopped; Fig. 5 also diagrammatically illustrates the invention, the portions appearing in full lines showing the condition which obtains when the ram is to be lowered from its uppermost position, the portions illustrated by dot and dash lines showing the condition which obtains when the ram has reached its lowermost position, the air motor then being stopped; and Fig. 6 is a sectional view on line 6—6 of Fig. 1.

A jack frame 1 may be of any usual or preferred construction, this frame terminating in an upper sleeve or cylinder portion 2 which is vertically arranged and serves as a guide for the ram 3 which is movable longitudinally or along its axis, that is, linearly. The ram 3 terminates in a load sustaining head 4 which is shown as being in the nature of a flange on the upper end of

the ram and which contacts with or is in close proximity to the upper end of the sleeve 2 when the ram is in its lowermost position. The ram is hollow and interiorly threaded to receive a jack screw 5 in threaded engagement therewith. This jack screw is shown as being in rigid connection with a horizontal bevel gear 6 which is supported by a thrust bearing structure which is inclusive of balls or rollers 7. The ram is raised and lowered by means of an air operated motor 8 of any preferred construction, this motor serving to drive the spur pinion 9 which is in mesh with a spur gear 10. A bevel pinion 11 is fixed with respect to and is coaxial with the spur gear, the bevel pinion being in mesh with the bevel gear 6. When the air operated motor is being driven by compressed air, it serves to turn the jack screw 5 through the intermediation of the gearing which has been described to raise or lower the ram.

The compressed air for operating the air motor is supplied to the motor from a suitable source of air under pressure and through the piping 12 which discharges into the annular passage 13 formed in a casing 14. The air flows from the passage through the radially aligned ports 15 in the hollow plug 16, said ports communicating with the bore 17 of said plug. Said bore discharges into the bore 18 of a hollow valve stem section 19, the bore 18, in turn, discharging through the port 20 in the valve stem section 19 and into the cylindrical clearance which intervenes between said valve stem section and the stationary upright sleeve 21 into whose upper end the plug 16 is screwed and which is clamped at its lower end in assembly with the tubular continuation 22 of the casing of the air motor by means of a nut 23. Said nut has an internal shoulder 24 which surrounds the sleeve 21 and is clamped downwardly upon the flange 25 of the sleeve, this flange being consequently clamped down upon the upper end of the tubular continuation 22 of the motor casing. A valve 26 (Figs. 4 and 5) is coupled with the hollow valve stem section 19 by the solid valve stem section 27, the clearance between the stem 100

portion 19 and the sleeve 21 being continued downward between the stem section 27 and the tubular continuation 22 of the motor casing. The valve 26 is contained within a casing 28 which is suitably disposed with relation to the air motor in accordance with common practice. The air which finds entry into the clearance between the two sections of the valve stem 19, 27 and the surrounding parts passes into the channel 29 that discharges into the valve casing 28. Channels 30 and 31 radiate from the valve casing which discharges into the one or the other of these latter two channels or into neither of them, according to the position of the valve. When the valve is in the position shown by full lines in Fig. 4, the motor is operated in the direction in which the ram 3 will be lifted, and when the valve is in the position shown by dotted lines in this figure, the motor is stopped, both channels 30 and 31 being then closed by the valve. When the valve is in the position shown by full lines in Fig. 5, the motor is operated in the direction in which the ram 3 will be lowered, and when the valve is in the position shown by dotted lines in this figure, the motor is stopped, both channels 30 and 31 again being closed by the valve.

30 The valve is turned by means of a lever 32 whose hub is journaled upon the sleeve 21 and which hub carries a pin 33 that passes through an elongated horizontal arcuate slot in said sleeve, this pin being screwed into the valve stem section 19, whereby the stem moves in company with the lever to operate the valve. The lever is formed with a handle portion 34 by which it is to be moved to effect either of the valve opening adjustments shown in Figs. 4 and 5 to effect the elevation and depression of the ram, respectively. The lever is automatically operated to occupy the position shown by dot and dash lines in Fig. 4 to close the valve when the ram has been brought to its uppermost position and is automatically operated to occupy the position shown by dot and dash lines in Fig. 5 to close the valve when the ram has been brought to its lowermost position. The mechanism 35 which is employed for automatically closing the valve is such as to permit the valve to be closed by hand when the ram is between its upper and lower limiting positions, and to permit it to be opened to operate the motor in 45 the proper direction only when the ram is in either of its extreme positions. The mechanism illustrated for effecting the automatic closure of the valve and that permits such manual operation of the valve is inclusive of a rocker arm 35, intermediately pivoted at 36 upon the housing bracket 37 which is provided upon the jack frame sleeve 2. This lever has a wing extension 38 which has an arcuate slot 39 therethrough, the long sides of this slot having their centers substantially in

the axis of turning movement of said rocker arm. A link 40 is connected at one end with an ear 41 which projects laterally from the lever 32, this end of the link being bent to pass through said ear. The other end of the link is also bent and passes through the aforesaid arcuate slot. Cotter pins may be employed to hold the ends of the link in assembly with the parts through which they pass. The end of the link which is received in said arcuate slot is adapted to travel in said slot from end to end thereof, the link thus being in lost motion relation with said rocker arm thereby permitting the valve to be manually brought to a closed position from either of its open positions and to either open position from its closed position, as will be clear by an inspection of Figs. 4 and 5. Dogs 42 and 44 are pivoted on the rocker.

Manual opening of the valve is required to effect vertical or lineal movement of the jack ram and while the valve may also be manually closed with the ram in any of its positions, yet it is important to effect the automatic closure of the valve when the ram has reached either limit of its travel to avoid injury. As illustrated in Fig. 1, and by full lines in Fig. 4, the valve has just been manually opened to effect the elevation of the ram of the jack. When the ram reaches the upper limit of its travel, the rocker arm 35 is automatically turned counterclockwise to bring the valve to its closed position to stop further elevation of the ram, the right hand end of the link 40 being then in engagement with the left hand end of the arcuate slot 39. This counterclockwise movement of the rocker arm occurs when the dog 42 is received within the annular groove or recess 43 formed in the ram near its lower end and is brought to the level of the nose of the dog when the ram has been raised to its upper limiting position.

As illustrated by full lines in Fig. 5, the valve has just been manually opened to effect the lowering of the ram of the jack. When the ram reaches the lower limit of its travel, the rocker arm 35 is automatically turned clockwise to bring the valve to its closed position to stop further lowering of the ram, the right hand end of the link 40 being then in engagement with the right hand end of the arcuate slot 39. This clockwise movement of the rocker arm occurs when the dog 44 is received within the annular groove or recess 45 formed in the ram and near its upper end and is brought to the level of the nose of the dog when the ram has been lowered to its lower limiting position.

Coiled springs or spring cushions 46 and 47 intervene between the ends of the rocker arm and the dogs 42 and 44, respectively. These springs operate to press the dogs 42 and 44 against the side of the plunger. When the ram approaches the downward limit of its travel, the dog 44 drops into the recess 45

and slight further downward movement of the ram acts to move the rocker in the clockwise direction, the dog then serving as a thrust connection. Similarly when the ram approaches the upper limit, the tip of dog 42 drops into recess 43 and slight continued upward movement of the ram acts through this dog as a thrust element to move the rocker in the counter-clockwise direction.

10 Changes may be made without departing from the invention.

Having thus described my invention, I claim:

1. In a lifting jack, the combination with 15 a vertically movable jack member, of an air operated motor in operating relation to said member; a valve for establishing and cutting off flow of operating air to said motor; a rocker arm connected with said valve to 20 close it; a dog upon the rocker arm; and spring means pressing said dog upon said member, the member having a recess which is positioned to receive the nose of said dog when the member has been brought to a predetermined position whereby the member acts 25 through said dog to turn the rocker arm to close the valve.

2. In a lifting jack, the combination with a vertically movable jack member, of an air 30 operated motor in operating relation to said member; a valve for establishing and cutting off flow of operating air to said motor; a rocker arm in lost motion connection with said valve to close it and to permit it to be 35 opened independently thereof; a dog upon the rocker arm; and spring means pressing said dog upon said member, the member having a recess which is positioned to receive the nose of said dog when the member has been brought to a predetermined position whereby the member acts 40 through said dog to turn the rocker arm to close the valve.

3. In a lifting jack, the combination with a vertically movable jack member, of an air 45 operated motor in operating relation to said member; a valve for establishing and cutting off flow of operating air to said motor; a rocker arm connected with said valve to close it; two dogs upon the rocker arm; and spring 50 means pressing said dogs upon said member, the member having a recess which is positioned to receive the nose of one of said dogs when the member has been brought to a predetermined position whereby the member 55 acts through said dog to turn the rocker arm to close the valve, said member having another recess which is positioned to receive the nose of the other dog when the member has been moved in a reverse direction to another predetermined position whereby the member 60 acts through this dog to turn the rocker arm to again close the valve.

4. In a lifting jack, the combination with a vertically movable jack member, of an air 65 operated motor in operating relation to said

member; a valve for establishing and cutting off flow of operating air to said motor; a rocker arm in lost motion connection with said valve to close it and to permit it to be 70 opened independently thereof; two dogs upon the rocker arm; and spring means pressing said dogs upon said member, the member having a recess which is positioned to receive the nose of one of said dogs when the member has been brought to a predetermined position whereby the member acts 75 through said dog to turn the rocker arm to close the valve, said member having another recess which is positioned to receive the nose of the other dog when the member has been moved in a reverse direction to another predetermined position whereby the member acts through this dog to turn the rocker arm to again close the valve.

5. In a lifting jack, the combination with 80 the ram thereof; of a jack screw in threaded connection with the ram; an air operated motor in turning relation to said jack screw for moving the ram; a valve for establishing and cutting off flow of operating air to 85 said motor; a rocker arm connected with said valve to close it; a dog upon the rocker arm; and spring means pressing said dog upon said ram, the ram having a recess which is positioned to receive the nose of 90 said dog when the ram has been brought to a predetermined position whereby the ram acts through said dog to turn the rocker arm to close the valve.

6. In a lifting jack, the combination with 95 the ram thereof; of a jack screw in threaded connection with the ram; an air operated motor in turning relation to said jack screw for moving the ram; a valve for establishing and cutting off flow of operating air to 100 said motor; a rocker arm in lost motion connection with said valve to close it and to permit it to be opened independently thereof; a dog upon the rocker arm; and spring means pressing said dog upon said ram, the member having a recess which is positioned to receive the nose of said dog when the ram has been brought to a predetermined position whereby the ram acts through said dog to turn the rocker arm to close the valve.

7. In a lifting jack, the combination with 105 the ram thereof; of a jack screw in threaded connection with the ram; an air operated motor in turning relation to said jack screw for moving the ram; a valve for establishing and cutting off flow of operating air to 110 said motor; a rocker arm connected with said valve to close it; two dogs upon the rocker arm; and spring means pressing said dogs upon said ram, the ram having a recess which is positioned to receive the nose of one of said dogs when the ram has been brought to a predetermined position whereby the member acts through this dog to turn the rocker arm to again close the valve.

8. In a lifting jack, the combination with a vertically movable jack member, of an air 115 operated motor in operating relation to said

other recess which is positioned to receive the nose of the other dog when the ram has been moved in a reverse direction to another predetermined position whereby the ram acts through this dog to turn the rocker arm to again close the valve.

8. In a lifting jack, the combination with the ram thereof; of a jack screw in threaded connection with the ram; an air operated motor in turning relation to said jack screw for moving the ram; a valve for establishing and cutting off flow of operating air to said motor; a rocker arm in lost motion connection with said valve to close it and to permit it to be opened independently thereof; two dogs upon the rocker arm; and spring means pressing said dogs upon said ram, the ram having a recess which is positioned to receive the nose of one of said dogs when the ram has been brought to a predetermined position whereby the ram acts through said dog to turn the rocker arm to close the valve, said ram having another recess which is positioned to receive the nose of the other dog when the ram has been moved in a reverse direction to another predetermined position whereby the ram acts through this dog to turn the rocker arm to again close the valve.

9. In a lifting jack, the combination of a standard, a lifting ram guided in the standard, a lifting screw coacting with said ram, an air-operated motor geared to the lifting screw, a valve for establishing and cutting off flow of operating air to said motor, manual means for operating said valve to start the motor in either direction and to stop it, and means for automatically shifting said valve to stop position when the ram reaches both upper and lower predetermined limits of motion, said means comprising elements on the upper and the lower portions of the ram, and a coacting controlling device operatively connected with the valve, said controlling device having its ram-coacting means disposed at one end of the standard to be actuated alternately by the upper and lower elements of the ram.

10. In a lifting jack, the combination of a standard, a lifting ram guided in the standard, a lifting screw coacting with said ram, an air-operated motor geared to the lifting screw, a valve for establishing and cutting off flow of operating air to said motor, manual means for operating said valve to start the motor in either direction and to stop it, and means for automatically shifting said valve to stop position when the ram reaches both upper and lower predetermined limits of motion, said means comprising recessed shoulders on the upper and the lower portions of the ram, and a coacting controlling device operatively connected with the valve, said controlling device having its ram-coacting means disposed at one end of the stand-

ard to be actuated alternately by the upper and lower shoulders of the ram.

11. In a lifting jack, the combination of a standard, a lifting ram guided in the standard, a lifting screw coacting with said ram, an air-operated motor geared to the lifting screw, a valve for establishing and cutting off flow of operating air to said motor, manual means for operating said valve to start the motor in either direction and to stop it, and means for automatically shifting said valve to stop position when the ram reaches both upper and lower predetermined limits of motion, said means comprising elements on the upper and the lower portions of the ram, and a coacting controlling device operatively connected with the valve, said controlling device being mounted for movement in opposite directions in a vertical plane and having its ram-coacting means disposed at one end of the standard to be actuated alternately by thrust of the upper and lower elements of the ram.

12. In a lifting jack, the combination of a standard, a lifting ram guided in the standard, a lifting screw coacting with said ram, an air-operated motor geared to the lifting screw, a valve for establishing and cutting off flow of operating air to said motor, manual means for operating said valve to start the motor in either direction and to stop it, and means for automatically shifting said valve to stop position when the ram reaches a predetermined limit of motion, said means comprising an element recessed in the ram, a controlling device having a dog to cooperate with said recessed element, and an operative connection between said dog and said valve.

13. In a lifting jack, the combination of a standard, a lifting ram guided in the standard, a lifting screw coacting with said ram, an air-operated motor geared to the lifting screw, a valve for establishing and cutting off flow of operating air to said motor, manual means for operating said valve to start the motor in either direction and to stop it, and means for automatically shifting said valve to stop position when the ram reaches both upper and lower predetermined limits of motion, said means comprising elements recessed in the upper and lower portions of the ram, and a coacting controlling device operatively connected with the valve, said controlling device having its ram-coacting means disposed at one end of the standard to be actuated alternately by the upper and lower elements of the ram.

In witness whereof, I hereunto subscribe my name.

JOHN W. HOBBS.
